UNITED STATES PATENT OFFICE.

ERNEST G. NUFFER, OF PHILADELPHIA, PENNSYLVANIA, ASSIGNOR TO GEORGE BROOKS & SON, OF SAME PLACE.

DESIGN FOR A CURTAIN FABRIC.

SPECIFICATION forming part of Design No. 15,877, dated February 24, 1885.

Application filed January 23, 1885. Term of patent 3½ years.

To all whom it may concern:

Be it known that I, ERNEST GARIBALDI
NUFFER, a subject of the Emperor of Germany, residing at Philadelphia, in the county
5 of Philadelphia and State of Pennsylvania,
have invented and produced a new and original Design for an Upholstery Fabric; and I do hereby declare that the photographic print accompanying this specification conveys to any 10 one skilled in the art a clear understanding of the same, and is sufficient to enable such person to use my invention.

What I claim as my invention, and desire to secure by Letters Patent, is—

The design for an upholstery fabric, as shown 15
in the photographic print accompanying this specification.

ERNEST G. NUFFER.
